UNITED STATES PATENT OFFICE.

WALTER R. BENJAMIN, OF CHINOOK, MONTANA, ASSIGNOR OF ONE-HALF TO THOMAS O'HANLON CO., INC., OF CHINOOK, MONTANA, A CORPORATION OF MONTANA.

WEATHERPROOF CONSTRUCTION FOR BUILDINGS.

1,379,516.

Specification of Letters Patent. Patented May 24, 1921.

Application filed February 26, 1920. Serial No. 361,548.

To all whom it may concern:

Be it known that I, WALTER R. BENJAMIN, a citizen of the United States, residing at Chinook, in the county of Blaine and 5 State of Montana, have invented a new and useful Weatherproof Construction for Buildings, of which the following is a specification.

This invention relates to weatherproof 10 construction for buildings.

The object is to provide means, in the form of metallic strips, for introduction between the abutting edges of adjacent boards 15 of frame buildings, the primary purpose of which is to prevent the leakage of moisture through the same and to cut off the passage of cold air, the device being so constructed and applied as to perform these functions even though the said boards may shrink or 20 warp to a considerable extent.

Another object is to provide a metallic strip for sealing the joint between the adjacent edges of weather boarding of buildings, which requires no nailing or other fastening means to hold the same in place and 25 which permits of the use of boards with plain smooth edges thus obviating the expensive operation of forming grooves, beads and overlapping portions of said 30 boards, and making it possible to cover a greater area with a given number of boards, the device also providing an ornamental strip along each of such seams or joints, thus adding to the appearance of the building. 35

A full and complete understanding of the invention may be obtained from a consideration of the following detailed description taken in connection with the accompanying drawing forming part of this specification, it being understood that while the drawing shows a practical form of the invention, the latter is not confined to strict conformity therewith, but may be changed 45 and modified, so long as such changes or modifications mark no material departure from the salient features of the invention, as specifically pointed out in the appended claim.

50 In the drawing,

Figure 1 is a vertical sectional view, showing a strip in position between two adjacent weather boards;

Fig. 2 is a similar view of another form 55 of strip;

Fig. 3 is a perspective view of a further modification in applied position;

Fig. 4 is a similar view of a still further modification.

The invention consists essentially in a 60 metallic strip, of substantial thickness composed of some such rust-resisting, non corrosive metal as galvanized iron, cut into suitable lengths for easy, economical and convenient handling of the same, say six 65 feet, this length being adapted to be best applied to the studding of buildings as commonly constructed.

Such a strip is bent to form an intermediate flat portion 2 extending throughout 70 its length, the marginal edge portions being then bent in opposite directions at right-angles thereto to provide a straight, flat flange 4, perpendicular to the intermediate portion 2 and likewise extending from end to end 75 of the strip.

The strip is adapted to be placed between the abutting edges of two weather boards 5 of the siding of a building, the latter being nailed to the usual studding 6 in the ordinary manner.

It is to be understood that the improved strips are to be placed in position one at a time during the course of construction of the building, as the boards are placed 85 against the studding and nailed thereto. After one board 5 is nailed the metal strip is placed thereon with the portion 2 of the same resting upon the top edge of the board and with the marginal flange 4 fitting flat against the inner face of the upper board and extending upwardly. 90

It is not necessary to nail the strip either to the top edge of the lower board 5, the bottom edge of the upper board 5 or to the studding, as it will be seen that the strip cannot become dislodged or removed from its position between the boards and that the latter are free to contract under the influence of atmospheric conditions, or to shrink from 100 other causes. It will also be seen that a tight seal under all conditions is provided between the boards to prevent the passage of wind or water, the nailing of the boards to the studding serving to hold the flanges 105 tightly against the respective faces of the boards.

In Fig. 1, the lower flange 3 is bowed outwardly so as to lie in spaced relation to the adjacent face of the lower board 5, the same 110

being held in such position by upper and lower beveled portions 7 and 8, the bevel 7 joining the flange 3 to the intermediate portion 2 and the lower bevel 8 having its free 5 edge bearing tightly against the outer face of the lower board 5, as clearly illustrated. In this form of the device, the lower flange gives the ornamental appearance of a beveled strip arranged along each seam of 10 the building, and has the further advantage of following up the face of the lower board, should the latter shrink in thickness, and thus maintains a tight seal. The flange 3 is given a normal tendency to spring inwardly 15 toward said board at all times by the resiliency of the metal comprising the strip 1.

Fig. 2 illustrates a somewhat similar strip, the lower half of the lower flange 3 being returned upon itself, as at 9, to lie between the 20 said flange and the adjacent face of the lower board 5, thus serving to give the said flange a thickened appearance and also materially strengthening the said strip.

In Fig. 3 the intermediate portion 2 of the 25 strip is nailed to the lower edge of the upper board 5, as indicated at 10, the nails or other fastening means serving to carry the strip with the board above in the event of shrinkage, indicated at 11, the space thus formed 30 being adapted to be effectually closed at all times by the outwardly and downwardly bowed, substantially semi-circular flange 13 extending from the outer edge of the intermediate portion 2 of the strip and having its 35 lower free edge 14 abutting against the outer face of the board 5 beneath.

In Fig. 4 there is illustrated another form 40 of strip, wherein the inner flange 4 is secured to the lower portion of the inner face of the board 5 by nails 15 or otherwise, and the space 11 which may be caused by shrinkage or otherwise, is adapted to be closed at 45 all times by the outer and downwardly extending flange 3 spaced away from the outer face of the board below by the beveled portions 7 and 8 as in the form shown in Fig. 1 of the drawing. In this form also the strip

is supported and carried by the board above and the gap 11 is effectually closed by the inherent tendency of the lower free edge of 50 the bevel 8 to hug the outer face of the lower board 5.

From the foregoing it will be seen that a simple and inexpensive means for closing the seam between the weather boards or siding 55 of buildings has been provided, which may be easily applied to the same and effectually serves to exclude water or wind, besides lending an ornamental appearance to the building. It also materially reduces the 60 cost as it is adapted to be used upon boards having plain, square abutting edges, thus eliminating the expensive tongue and groove, ship lap, drop siding, or the ordinary overlapped joints, which require extra 65 milling and require a considerable amount of material to produce. Furthermore, the boards are prevented from warping by the said strips and the seams are rendered rat, mouse and vermin proof thereby. The strips 70 are easily manufactured from stock material and may be bundled and shipped economically and conveniently.

What is claimed is:—

The combination with two adjacent boards 75 placed edge to edge, of a metallic strip having a flat intermediate portion extending longitudinally throughout its length and adapted to fit between the opposed edges of 80 said boards, a perpendicularly disposed flange extending from the inner edge of said portion and fitting against the rear face of one of the boards, and another flange extending from the outer edge of the intermediate portion in a direction opposite to 85 the first-named flange, said last-named flange being bowed outwardly and having its lower edge bearing against the other board at a point remote from the meeting 90 edges of said boards.

In testimony, that I claim the foregoing as my own I have hereto affixed my signature.

WALTER R. BENJAMIN.
